CLAIM

The ornamental design for a vertical file for computer monitor, as shown and described.

DESCRIPTION

FIG. 1 is a top, right front perspective view of a vertical file for computer monitor showing my new design, the partial showing of a computer monitor depicted by means of broken lines being shown for illustrative purposes only and forming no part of the claimed design. FIG. 2 is a front elevational view thereof; FIG. 3 is a right side elevational view thereof; FIG. 4 is a top plan view thereof; FIG. 5 is a left side elevational view thereof; FIG. 6 is a bottom plan view thereof; and, FIG. 7 is a rear elevational view thereof.
